[57] **CLAIM**

The ornamental design for a blank for a combined vent and baffle, substantially as shown and described.

DESCRIPTION

FIG. 1 is a front elevational view of a blank for a combined vent and baffle showing my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is an enlarged cross sectional view taken on line 7—7 of FIG. 1; and

FIG. 8 is an enlarged cross sectional view taken on line 8—8 of FIG. 1.

It is to be understood that the dash lines in FIG. 1 represent slits in the blank as indicated in FIG. 7.

FIG. 2**FIG. 3****FIG. 1****FIG. 4**

FIG. 5**FIG. 6****FIG. 7****FIG. 8**
